United States Patent Office

Des. 183,036

Patented June 17, 1958

183,036

SPRAY CAP UNIT

Donald F. Armour, Bloomfield, Conn., assignor to Plax Corporation, Bloomfield, Conn., a corporation of Delaware

Application June 24, 1957, Serial No. 46,693

Term of patent 14 years

(Cl. D83—1)

FIG. 6

FIG. 1

FIG. 2

FIG. 4

FIG. 3

FIG. 5

Fig. 1 is a perspective view of a spray cap unit embodying my design;

Fig. 2 is an enlarged top plan view of the spray cap shown in Fig. 1 with the closure shown in closed position;

Fig. 3 is a side elevation view thereof;

Fig. 4 is a front elevation view thereof;

Fig. 5 is a rear elevation view thereof; and

Fig. 6 is a view similar to Fig. 3 with the closure in open position.

I claim:

The ornamental design for a spray cap unit, as shown.
